Primary Examiner — Rashida C. Walshon(74) *Attorney, Agent, or Firm* — Polsinelli PC(57) **CLAIM**

We claim the ornamental design for a slip-on shoe, as shown and described.

DESCRIPTION

FIG. 1 is a perspective view of a slip-on shoe;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof;
FIG. 7 is a bottom plan view thereof; and,
FIG. 8 is a perspective view thereof showing an environment related to the slip-on shoe.
Broken lines are used to illustrate unclaimed portions and/or for illustrating an environment related to the claimed design of the slip-on shoe; broken lines form no part of the claimed design.
